UNITED STATES PATENT OFFICE.

ROYCE L. BEERS, OF DETROIT, MICHIGAN, ASSIGNOR, BY MESNE ASSIGNMENTS, TO
RILEY STOKER CORPORATION, OF WORCESTER, MASSACHUSETTS, A CORPORATION
OF MASSACHUSETTS.

UNDERFEED STOKER.

Application filed June 16, 1922. Serial No. 568,797.

The present invention in underfeed stokers relates more particularly, in some of its features, to what are now sometimes called "lateral branch retort stokers," that is to say, 5 constructions in which the fuel is initially introduced into a main retort running in one direction, and whence part of the fuel is distributed to other retorts that extend laterally, or generally transversely to the direction 10 of the main retort, with their fuel-receptive ends toward the main retort. Structures of the general type referred to are known, as in Kleffel Patent 1,270,171, dated June 18, 1918 (Reissue 14,747), and Armstrong and 15 Blackburn, No. 1,333,696, issued March 16, 1920.

Some of the features of my present invention relate more particularly to installations of stokers of the character described in which 20 the lateral retorts are located at one side only of the main retort, and in this regard an object of my invention is to provide improved and advantageous structure for properly maintaining desired combustion conditions 25 along the blank side of the fire-box, effectively free from disadvantageous clinkering, and in a manner desirable to promote effective distribution of the fuel through the combustion area served by the lateral retorts.

30 In other aspects my invention has further to do with a means for feeding fuel in a stoker of the general character described, and has for its object to provide advantageous and cooperating retort structure and feeding 35 means to aid in securing and maintaining efficient combustion conditions throughout the effective area of the fire-box or combustion chamber floor, and also in the movement and disposition of ash or refuse of combustion.

40 Further, my invention has to do with the mechanical construction of stokers of the general character described, with the object of attaining greater simplicity, economy of manufacture and use, ruggedness, durability, 45 and facility in manufacture and installation of such stoker construction.

With a view to attaining these and other objects which will become apparent to those skilled in the art from the following description taken in conjunction with the accompanying drawings, my invention consists in the combinations and features of construction hereinafter set forth by exemplification in a single embodiment, as to which embodiment it will be understood that numerous

changes in details of construction and arrangement may be made without departure from the spirit of my invention and within the scope of the claims hereto appended.

In the drawings, Fig. 1 is a front elevation 60 of a furnace equipment embodying my invention; Fig. 2 is a vertical longitudinal section on the plane 2—2 of Fig. 1, looking in the direction of the arrows; Fig. 3 is a plan view, with parts in section on line 3—3 of 65 Fig. 2; Fig. 4 is a transverse section on line 4—4 of Fig. 3; Figs. 5 and 6 are details in side and front elevations of tuyère plate construction; Fig. 7 is a detail section on the line 7—7 of Fig. 4; Figs. 8 and 9 are sections 70 through a corner-tuyère, Fig. 8 being taken on the line 8—8 of Fig. 9 and Fig. 9 on the line 9—9 of Fig. 8; and Fig. 10 is a perspective view of a corner-tuyère.

It will be understood that in the drawings, 75 for clarity of illustration, working scale has not been observed, pertinent stoker parts being generally shown exaggeratedly, and auxiliary structures reduced in size.

In general, it will be understood, that green 80 fuel from a supply hopper 10 is fed through a front-wall throat 11 into a main longitudinal retort 12 by the reciprocation of a suitable ram 13, suitably driven in any way as by ram-engine 14.

The green fuel thus fed into the main retort 12 is, in part, ultimately consumed in the combustion area directly above the main retort, but other portions of fuel, more or less affected by the passage through the main 90 retort, will be distributed to lateral retorts 15 for consumption in the further area served by these retorts. Of these lateral retorts generally arranged side by side and extending in a direction transverse to that of the main 95 retort, a suitable plurality may be provided dependent in number on the length of the main retort and the desirable width of the lateral retorts.

These retort structures form part of a firebox floor, generally indicated at 16, which, as a whole, extends from the front wall 17 to the bridge wall 18 and from one side wall 19 to the other side wall 20 of the boiler setting, the retorts proper being supplemented in this floor formation, by suitable extension surfaces and by ash-dumping surfaces paralleling the outer or delivery ends of the lateral retorts. The space 21 above the floor may, as a whole, be called the combustion 110

space, while below the floor division is made as by a partition structure 22 into an ash pit 23 below the ash dump 24, and a wind-box 25 into which air under pressure is constantly introduced from a suitable source of supply. Air from the wind-box finds emission through the tuyère openings, generically indicated at 26, around the margins of the retort structure to support combustion in the chamber 21, and if desired a damped orifice 27 to the ash pit may permit a regulated supply of air to flow to the dump plate, both to cool the latter and to complete the combustion of any partly consumed matter that may lodge on the dump plate in the forcing of the stoker operation, as under boiler-overload.

With the very widespread area of active combustion that may be fed from a single source of supply of fuel, and a single main retort, it is feasible and oftentimes desirable to construct the stoker with lateral retorts along one side only of the main retort, thus locating the main retort near one side of the boiler-setting, and such a construction I have specifically illustrated in the drawings. The main retort 12 is relatively close to the side-wall 20, and lateral distribution of fuel is only toward the right (Fig. 4), toward the single dump mechanism 24. It is usually desirable that the mouths of the lateral retorts have a distinct down-slope from receiving end to delivery end, so that the dump structure 24 is considerably lower than the mouth of the main retort, and therefore the high point of the fuel bed is apt to be near the blank side of the retort and adjacent the wall 20. Further it is my preference that the mouth of the main retort be substantially horizontal, and since the feed of the combustible in this locality is longitudinal or parallel with the furnace side-wall, I space the blank side of the main retort somewhat away from the side wall and provide tuyère structures spanning from the blank wall of the retort to the furnace side wall of such character and construction as to prevent or minimize possibility of clinker-adhesion that might interfere with the feeding action. Further, although distribution of combustibles from the main retort to the lateral retorts may variously be accomplished, it is my preference that the inner or receptive ends of the lateral retorts shall be in open communication throughout all, or a large portion of, their cross-sectional area with the main retort, so that expulsion of fuel from the main retort to the lateral retorts may be easy. And, in the construction of the blank side of the main retort, and its appurtenances, I preferably provide structure for aiding in the distribution of combustible from the main retort to the lateral retort.

Thus, in the specific construction shown each of the lateral retorts 15 opens directly to

the main retort through the right-hand side wall of the latter, and the left-hand or blank side wall is surmounted by an upright edge plate 29 bolted thereto and having along its upper edge an outwardly turned flange 30. 70 Surmounting this extension-piece of the blank side wall of the retort is a non-clinker tuyère structure 31, extending full length of the main retort, and preferably constructed and arranged to assist in the fuel-distributive action. This structure is preferably composed of a series of narrow tuyère-plate units of identical construction, interlocked in position between the flange 29 and the furnace side-wall and spanning the space 80 between the two. This multiple plate structure preferably provides, as portions of the fire-box floor, one inclined surface 32 contacting with the side wall at a point high enough above the topmost point of the tuyère blocks for the lateral retorts to include the normal zone of clinker-formation and sloping downwardly, inwardly, or toward the axial vertical plane of the main retort, to a line preferably above but between the edges 90 of the main-retort mouth, and another surface, roundedly merging with the first, that extends downwardly but back toward the side wall of the retort to a line of juncture with the edge plate 29. Thus, as shown in 95 Fig. 4, the upward extension of the retort's blank wall, afforded by these surfaces, provides a re-entrant or overhanging shoulder against which the upthrust of fuel may take effect to divert its force laterally toward the 100 laterally extending retorts.

In specific construction I preferably form each unit 34 of the stated structure 31 in the manner specifically indicated in Figs. 5 and 6, that is to say, to provide a plate body or thin web 37 having a marginal flange 38 bordering all but its bottom edge. Notches 39 and 39' through such border, in appropriate positions, will afford tuyère openings 39 through surface 33 and small air ports 39' at the top of surface 32 to cool the furnace-wall. Immediately below each of the tuyère-openings 39 a rib 40 preferably runs backwardly and upwardly along the plate to tend to prevent the passage of fuel particles and ash into the air space between adjoining plate webs. The lower margin of the plate body is provided with a hook 41 to engage the flange 30 and lock the plate with its vertical, flanged edge flush against the furnace side wall. A retaining rod 42 may be run through aligning apertures in the several plates if desired. It will be noted that even if the surfaces of these plate-structures should be burned off, the closely spaced body webs would prevent the fuel from falling through to any serious extent, and the body webs also serve to minimize the danger of burning out, by carrying away the heat.

In the construction of lateral retort stokers 130

it is now known practice to dispose the bottom of the main retort at one level, arrange the lateral retorts with their bottoms at a level lower than this, and to provide channels, 5 below the bottom level of the main retort and opening into the lateral retorts, in which to locate cross-feed mechanism for the lateral retort to supplement the fuel-feeding action of the feeding devices associated with the 10 main retort. I find that in a stoker so characterized efficacy in fuel-distribution and in fuel consumption and ash disposal are aided, and results improved, by structure which I will now describe. Both the main and the 15 lateral retorts are made quite shallow. The bottom 45 of each lateral retort preferably has its inner portion flat and arranged horizontally, but toward its outer or delivery end it up-slopes as at 47 to a 20 marginal flange 48. The horizontal portion 46 finds effective continuation in the bottom wall 49 of the channel 50 transversely traversing the bottom portion of the main retort. In each of these channels is arranged 25 a feed block 51, having a fin 52 extending down through a slot 53 in the channel-bottom 49 and carrying guide rollers 54 that act on the margins of the slot. This block is preferably of such length that at all times it covers 30 the slots and it is reciprocable from rock shaft 55 through lever arm 56 and link 57, the latter connectible to the arm at varying distances from the axis of oscillation of the shaft to vary the length of throw of the feed 35 block. At its active end (or at both ends if used in a furnace having two sets of lateral retorts), this feed block is preferably formed for both horizontally moving and up-thrusting the fuel, preferably by the provision of an 40 upper shoulder 58, approximately vertical in position, and therebelow a protruding beveled nose 59 that slopes from the shoulder downwardly and outwardly to the bottom of the block, or at an inclination opposite to 45 slope 47 of the retort-bottom. Feeding of the fuel longitudinally of the main retort is effected primarily by the operation of the ram 13, but may be furthered by the provision of a reciprocable feed plate 61 extending 50 through the throat and along the flat bottom of the main retort, preferably from side to side thereof, and provided with one or more upstanding feed blocks 62. I preferably employ two feed blocks 62 and 62', the rear block 55 62 being the deeper and having a substantially vertical rear end 63 and a top surface 64 gradually inclined downwardly to its front end. The other, shallower block 62' preferably has its rear end 63' steeply inclined to 60 project at its bottom and its top-surface 64' gradually down-sloped to the front. The plate 61, running over and covering the transverse feed blocks 51, is guided in brackets 65 on the retort-walls and is reciprocated by a lost-motion connection at its outer end with the ram, a pendant arm 66 of the ram engaging between adjustable stop pins 66' of the plate extension. A check plate 67 secured in the throat extends over and guides the feed plate 61 and its abrupt shoulder stops 70 any tendency of the fuel to follow the feed plate into the throat. For operating the rock shaft by which all of the lateral feed blocks are reciprocated, a lever 68 is provided on the end of the rock shaft and is suitably vibrated 75 by an engine 69, suitably controlled in operation-periodicity.

I find that with the lateral retorts relatively shallow, and having the inner portions of their bottoms horizontal and the delivery portions thereof up-sloped, the horizontally traveling feed blocks both propel and lift the fuel with an efficacy that gives most excellent distribution of the fuel and at the same time tends most strongly to prevent clinker-formation by adequately breaking up the fire, keeping the live fuel-bed actively stirred and properly distributed for the full and effective action of the air which is emitted to the bed 80 through the tuyères. The flat feed plate, pusher-block equipped, tends to carry fuel rearward to some extent, while upon its retracting action the inclined surfaces of the pusher-blocks have a lifting and loosening action with respect to the coal that is very 85 beneficial in preparing it to be fed either along the main retort or into the lateral retorts.

The mouths of the lateral retorts may be 90 located with their outer edges somewhat removed from the dumping zone, and the intermediate space from the retort ends to the dump plate may be bridged by end plates 70, either somewhat perforated or dead-plates. At the front and rear of the fire-box structure air-cooled dead plates may steeply up-slope from the margins of the extreme lateral retorts which are respectively proximate to the furnace front wall and to the bridge wall, to meet these furnace walls at a high 95 enough level to protect them, as best shown in Fig. 2, the under sides of these plates being open to the wind-box so as to be kept cooled by the air therein. These plates may be imperforate but are otherwise of substantially the construction of plate-tuyères 31.

In the particular construction shown, the body casting for each branch retort is separately made, and flanged as at 75 along its receptive end which is to be connected with the main retort structure. These castings may be all alike and of any desired length. The main retort is formed of a plurality of longitudinally adjoining sections, one for each lateral-retort position, these sections being flanged as at 77 at their abutting edges, to be suitably secured together as by bolts. Each such section has at its forward and rear edges respective halves of two side wall posts 78, and the outer margin of the post casting 100

105

110

115

120

125

is flanged as at 79 to receive the flange 75 of a lateral retort-casting. In this way, specifications for various areas of retort-capacity may be satisfied by assembly of different numbers of main retort sections with lateral retort sections of proper dimensions. At the rear end of the main retort the last section may have its extremity closed by a suitably shaped filler plate 80 as shown in Fig. 2, bolted in to close the rear end of the main channel and this plate may be recessed or apertured as at 81 to receive the end of the feed plate 61. To reduce casting-size, each main-retort section may be further divided into pieces meeting in a horizontal plane and bolted together to form a section-unit, but this is not always desirable.

The tuyère blocks 82, spanning the air-trunk 83 between the side walls of adjoining lateral retorts, and mounted on the flanged side-margins of said retort castings, may be of plate form, disposed in generally upright arrangement side by side, supplemented by suitable corner tuyères 84 forming the tops of the side wall posts.

These corner-tuyères are especially subject to hard usage and are preferably specially constructed for facility of replacement, at minimum expense, for efficacy in air-distribution in all directions, and to hold up the fire even when partly burned away. In detail I construct each such corner-tuyère of a plurality of complementary thin-sections interlocking to give a firm assembly and shaped in the aggregate to present in their upper portion a rounded contour, nearly quarter-spherical in effect, for exposure to the fire, with tuyère openings in all directions of such surface, and in their lower portion to make up a stem for insertion into the air-trunk space between two lateral retorts. In detail five sections or layers are shown, although more or less may be used, these sections 84^a, 84^b, 84^c, 84^d and 84^e, having each a head portion (85^a to 85^e), and a stem portion (86^a to 86^e). Each section has a plate-web (87^a to 87^e), marginally bordered throughout the exposed head part by a flange-run (88^a to 88^e) through which flanges the tuyère openings are made, each leading to an interspace between body-webs. The stem portions have interlocking and spacing lugs (89^a to 89e) thereon to position the layers in assembled relation, and all stems may be notched as at 90 to engage the flanges of the lateral retorts. The planes of severance between the layers are preferably nearly parallel between the stem portions but through the heads sweep on curves of progressively shorter radius for uniform distribution of the tuyère openings and stronger interlock.

To afford support for the metallic structure forming the fire-box floor, the partition 22 may in part be composed of a partition plate casting 92 having suitable footings

and brackets for sustaining the associated parts. In this plate the dampered orifice 27 may be formed, and on the plate may be supported the rock shaft 93 for the ash dump platform 24, such shaft (as shown in Fig. 1) running through the front of the furnace for manual operation by a detachable crank not shown. Cross-beams 94, extending from suitable footings on said partition plate to the wall 19, afford support for the main retort casting and may be supplemented by a longitudinal beam 95 to support the outer ends of the downwardly-inclined flanges of the lateral retort castings. On these cross-beams 94 is supported the rock shaft 55 of the feed mechanism for the lateral retorts.

The ash dump platform 24 is preferably made in rather narrow sections for easy replacement, each being shaped for detachable engagement at its inner end with the square rock-shaft 88, and near its outer end provided at opposite sides with a tongue 97 and a tongue-receptive notched lug 98 so that a series of these duplicate plates may be interlocked. Also the plates are preferably perforated for air-passage therethrough, each plate having a side edge notched as at 99 for this purpose.

I claim:

1. In a furnace having walls, a wind-box space, and a combustion space, a floor structure separating said wind-box space from said combustion space, said floor structure comprising a main retort spaced from and running substantially parallel to one wall of the furnace, a plurality of lateral retorts extending across toward the opposite furnace wall, such lateral retorts being spaced apart from each other and having marginal tuyères that are highest adjacent to the main retort, and a tuyère-structure spanning the space between the first-mentioned furnace wall and the adjacent side of the main retort and open to the wind-box space, said tuyère structure extending up materially above the level of the highest tuyères for the lateral retorts to include, at a lower level than the top lines of said highest tuyères for the lateral retorts, the normal zone of clinker formation, and said tuyère structure having its tuyère opening near the level of the highest tuyères of said lateral retorts.

2. In a furnace having walls laterally enclosing a combustion space and a wind-box space therebelow, a stoker floor-structure separating the wind-box space from the combustion space, said floor structure comprising a main retort spaced from and running substantially parallel to one said wall of the furnace, a plurality of lateral retorts extending across toward the opposite furnace wall, these being spaced apart from each other and having marginal tuyères communicating with said wind-box space, and a structure bridging the space between the first said furnace wall

- and the adjacent side of the main retort and shaped to overhang said main retort for directing fuel toward the lateral retorts, said overhanging structure including overhanging portions that are located directly opposite the places where the inner ends of said lateral retorts receive fuel from the main retort; and means for feeding fuel along the main retort.
3. In a furnace having walls enclosing a combustion space and a wind-box therebelow, a stoker floor-structure separating said wind-box from said combustion space, said floor-structure comprising a main retort spaced from and running substantially parallel to one wall of the furnace, a plurality of lateral retorts adapted and arranged to receive fuel from said main retort at their inner ends and extending across toward the opposite furnace wall, these lateral retorts being spaced apart from each other and having marginal tuyères communicating with the wind-box, and a structure bridging the space between the first-mentioned furnace wall and the adjacent side of the main retort, shaped to provide near its bottom a portion bulging inwardly over the main retort and to provide thereabove a portion out-sloping to the furnace wall to meet the latter at a height that will include below its upper level the normal zone of clinker formation, and parts of such inwardly bulging portion being disposed directly opposite the fuel-receptive inner ends of said lateral retorts.
4. In a furnace of the character described, the combination with the furnace walls of a main retort extending parallel and adjacent to one furnace wall, said main retort having a blank side toward said wall and having openings through its opposite side, lateral retorts communicating with said main retort openings and extending across toward the opposite wall of the furnace, means for feeding fuel longitudinally of the main retort, and a structure surmounting the blank side of the main retort and overhanging the latter, at places directly opposite the openings to the lateral retorts for directing fuel, up-thrust by the feeding means for the main retort, toward the lateral retorts.
5. In a stoker structure of the character described, the combination of a plurality of lateral retorts arranged side by side, a main retort crossing the inner ends of said lateral retorts in arrangement to deliver fuel thereto, said main retort having along its side at places directly opposite the said lateral retorts overhanging portions disposed to direct up-thrust fuel toward the respective lateral retorts, and means for feeding fuel longitudinally of the main retort and causing up-thrust of fuel.
6. In a stoker of the class described, the combination of a main longitudinal retort, lateral branch retorts to receive fuel from the main retort and each having a substantially horizontal bottom portion at its fuel-receptive end, a feed ram for the main retort, and laterally reciprocable pushers in the branch retorts, each said pusher being located in the horizontal fuel-receptive portion of its lateral retort and each having a projecting nose providing a surface inclined to present its lower edge in advance of its upper edge in the direction of feeding movement.
7. In an underfeed furnace, a main retort having its bottom at one level, lateral branch retorts having their bottoms at a lower level, the bottom of each lateral retort having a horizontal portion adjacent the main retort and an up-sloped portion adjacent the other end of the lateral retort, and a pusher block horizontally reciprocable along the bottom of each lateral retort and providing a projecting nose sloped oppositely to the end slope of the retort.
8. In an underfeed stoker having a main retort and lateral retorts at one side only of the main retort, a tuyère plate structure providing a portion to overhang the blank side of the retort and comprising a body web, a marginal flange thereon to provide a downwardly and inwardly sloping upper surface, and a downwardly and outwardly sloping overhang surface having tuyère notches.
9. In an underfeed stoker having a main retort and lateral retorts at one side only of the main retort, a tuyère plate structure providing a portion to overhang the blank side of the retort and comprising a body web, a marginal flange thereon to provide a downwardly and inwardly sloping upper surface, and a downwardly and outwardly sloping overhang surface having tuyère notches, and said plate having at its bottom a hook to interlock with a portion of the main retort.
10. In a stoker of the character described, the combination of the longitudinal main retort, lateral retorts extending transversely thereto and each having an opening in its bottom, respective pusher blocks in the lateral retorts each having a depending portion extending through the respective opening in the retort bottom, a rock shaft, levers on said rock shaft, and respective links connected with the depending portions of the several pusher blocks and each having independently adjustable connection with a corresponding lever of the rock shaft.

ROYCE L. BEERS.
